Application November 23, 1935, Serial No. 51,328

1 Claim. (Cl. 83—94)

This invention relates to the separation of heterogeneous mixtures of solid fragments having different densities, and contemplates the provision of improvements in methods of and apparatus for effecting such separation. More specifically, the invention contemplates improvements in the separation of two or more minerals or other solids having different specific gravities by employing gravitational forces in the presence 10 of a heavy medium.

In the heretofore customary practice of ore dressing and allied arts, mixtures of mineral particles having different densities have been separated by adding the mixture to a fluid of relatively heavy density. Under such conditions the particles having a density greater than that of the fluid tend to sink, whereas particles which are lighter than the fluid tend to float. The products thus become separated and may be withdrawn 20 separately from different zones.

Theoretically at least, the ideal medium is a heavy fluid, such as an aqueous salt solution of high specific gravity or a heavy organic liquid such as tetrabromethane ($C_2H_2Br_4$). However, such fluids are relatively expensive. Attempts have been made heretofore to replace such heavy fluids with multiphased mixtures of finely divided solids with liquids (usually called "suspensions"). Throughout the present specification the terms 30 "medium" and "heavy medium" are used to include these multiphased mixtures of finely divided solids (such as galena) with liquids (such as water).

Due to the fact that heavy media tend to be- 35 come contaminated with ore fines, etc., and due to the fact that there is a tendency for particles to settle out of the medium, they do not act as true fluids. These facts have been responsible for the failure of many prior proposals for separating heterogeneous mixtures of solid fragments by immersing them in heavy media. When such media are fresh, the processes of some prior proposals are relatively efficient. However, attempts at continuous operations of this character have 40 proved disappointing, chiefly, I believe, because of the failure to remove contaminating substances from the medium and to maintain the density and the consistency of the medium relatively constant at all times within the separating chamber. 45 Another element which has contributed to the economic failure of prior continuous processes is the fact that inadequate steps have been taken to prevent the loss of the relatively valuable heavy medium. Furthermore, the fouling of the medium 50 with oils from the machinery employed and with

colloidal gangue materials that form practically permanent suspensions in water (even in a relatively high state of dilution) has prevented the commercial application of continuous processes of this character except when there was a relatively great difference in specific gravity between the materials to be separated or when the gangue material itself may be used to make the medium. 5

As a result of my investigations, I have discovered that the separation of mixtures of solid 10 fragments having different specific gravities is greatly facilitated, especially in a continuous process, if one or more of the following procedures are observed:

(1) The feed to be treated should be first thor- 15oughly washed with water to remove possible contaminants, either small solid fragments or soluble or colloidal impurities. This washing step is preferably performed in a countercurrent washing or screening operation, that is to say, the feed is 20 passed progressively over a screen or series of screens (or classifiers) to the last of which clear water is supplied. The drainage from the clear water screen is then freed of sands and used over again for washing. In other words, the clear 25 water first comes in contact with the material which is already fairly clean while the dirtiest water is used to treat the feed as it is first introduced into the washing operation. 15

(2) After this preliminary washing the film 30 of water on the fragments of feed should be sub- stantially reduced in amount. I have found that the most advantageous way of doing this is to pass the feed over a screen onto which the heavy 35 medium is fed. In this way the film of water on the fragments is replaced by a film of medium. Subsequent dilution of the medium in the sepa- rating chamber is prevented effectively in this 40 way. The amount of moisture retained on the fragments after the preliminary washing is like- 45ly to vary within wide limits, depending upon the proportion of fines present in the feed. Conse- quently, if this moisture were permitted to enter the separating chamber, there would be a variable dilution of the medium therein, and consequently 50 a variation in medium density. Such dilution in a separating chamber increases the amount of 55 circulating load of make-up medium to be handled in the circuit, and is therefore objectionable. On the other hand, it is not desirable to introduce the fragments into the chamber in an absolutely dry state because separation in the chamber is thereby impeded, and the subsequent removal of the medium from the fragments is made more difficult. In the case of coal or other minerals of

low economic value where the medium is derived from the ore itself and a substantial loss of medium is of no economic consequence, the dry ore may be wetted with medium direct. The amount of moisture accompanying the fragments may be substantially reduced if they are first subjected to a gaseous blast which tends to remove at least a part of the water. This means of control is, however, not as desirable as the aforementioned replacement of the water film on the fragments with a film of medium.

(3) The separating medium and the fragments to be separated should be continuously introduced into the separating chamber, preferably near the top and the center of the chamber. I have also found that it is practically essential to withdraw the heavy fragments which settle to the bottom of the chamber substantially continuously together with a portion of the medium in order to secure a properly refined separation. The coarser solid particles in the medium, together with any sandy constituents of the feed, tend to settle out in the bottom of the chamber, thus increasing the density of the column at this point and causing so-called "crowding" of the ore particles to be separated. This crowding must be prevented, or at least substantially offset, by withdrawing the material substantially continuously from the bottom of the chamber, and varying the rate of such withdrawal in response to variations in the density of the medium or volume of heavy material at the bottom of the chamber. In this way undesirable crowding in the separating chamber is avoided and at the same time the density of the separating medium from top to bottom of the chamber is maintained with but slight increase from top to bottom.

(4) I have found it essential to so condition the medium before it is introduced into the separating chamber that substantially all of the sands and undesirable intermediate sizes of particles are removed therefrom. I have also found it necessary to maintain the density of the medium at some predetermined and substantially constant value. In order that the medium may meet with this requirement, I introduce it into a classifier of novel design and there remove the undesirable coarse constituents from the medium, at the same time controlling the ratio of liquids to solids so as to obtain the desired predetermined density, as well as the volume being introduced into the separating vessel.

(5) For economical operation and to prevent the handling of excessive quantities of liquid in the circuit, I have found it desirable to drain off the medium accompanying the concentrates and the tails or middlings removed from the separating chamber before washing these products. The medium thus drained is returned to the separating chamber after the aforementioned conditioning.

(6) Following the drainage of the separated products, in order to reduce the volume wash water which must be thickened, I find that countercurrent washing of the products is necessary. This feature of countercurrent washing will be more thoroughly discussed in succeeding paragraphs.

(7) It is also desirable to remove sandy material from the wash water between each stage in the countercurrent washing operation of the products.

(8) To prevent an undue accumulation of objectionable colloidal constituents in the circuit I find that it is necessary to bleed off a proportion

of the overflow from the thickener or other means employed to increase the density of the medium (removed in the washing operation from the product and returned to the circuit after thickening). It is also essential to remove any oil or froth from the circuit and I find it expedient to remove this oil in a froth trap following the thickener overflow.

(9) To prevent an undue loss of valuable medium and at the same time to utilize water as completely as possible, it is necessary to maintain a proper water balance in the circuit. That is to say, the amount of fresh water supplied to the washing operations should approximately equal the amount of water removed from the circuit as entrained moisture, plus the water which is bled out of the circuit at the overflow of the froth trap.

These and other important elements of my discovery will become more clear if reference is made to the accompanying drawings, in which

Fig. 1 is a flow-sheet of an ore dressing plant incorporating the elements of my invention, and

Fig. 2 is a schematic representation in section of a secondary separator of my design.

Referring now to Fig. 1, crushed ore of an appropriate size, say $\frac{1}{2}$ inch to 1 inch in diameter, is fed from a crushed ore storage bin 1 onto a preliminary washing screen 2, where it is washed in countercurrent by sprays 3, 4, and 5 in series. Fresh water is supplied to the spray 5. The drain from the spray 5 is caught in a sand trap 6 and the overflow water from this sand trap is passed through a pump 7 into the spray 4. Similarly, the drain from spray 4 is caught in a sand trap 8. The overflow from the sand trap 8 is passed through a pump 9 into the spray 3. The drain from spray 3 is caught in sand trap 10 and the overflow from this sand trap is sent to the thickener 11.

The preliminary screen is preferably of the vibrating type and of about 20 meshes to the inch. The sands washed through the screen are, therefore, minus 20 meshes in size. The sands from the three traps 6, 8, and 10 are sent to a classifier 12 in enclosed circuit with a ball mill 13. The finely ground product of this ball mill is then sent to an ore thickener 11. The purpose of the initial screening operation and the aforementioned subsequent trapping and grinding operations is to remove from the feed fine material which cannot advantageously be separated in a heavy medium. The sands and slimes thus removed are thickened so that they may be treated by flotation or other appropriate process in the event that their value warrants recovery.

The sand traps may be of any appropriate design.

From the preliminary washing operation the oversize is sent to a box 14 into which is also continuously introduced a portion of the heavy medium. The mixture of medium and washed oversize then passes over a screen 15 of the vibrating or conveying type. In this way, the water film present on the washed oversize is in large part replaced by a film of medium. The aforementioned medium draining screen 15 is of approximately the same mesh as the initial or preliminary washing screen. After leaving the screen 15, the oversize now coated with a film of medium is introduced into a separating vat 16. The undersize of the screen 15 is chiefly excess medium accompanied, however, by some attrition products formed on the screen plus fine material which was not removed in the pre-

liminary washing operation. The undersize of the screen 15 is sent to a subsequent operation hereinafter described for the removal of the foreign material and the recovery of the medium.

5 The separating vat 16 is preferably of conical construction, or at least the bottom of the vat should be conical with the apex of the cone downward. Within the cone is provided a downwardly extending hollow shaft 17. This shaft is provided 10 with blades 18, 19 and 20. The pitch of these blades may be adjusted. Means, not shown, are provided for revolving the shaft and the associated arms at a relatively low rate of speed. The peripheral speed of the end of the blades should 15 not exceed 150 feet per minute. The purpose of the blades is not so much that of agitation as it is to impart a centrifugal impulse to the material introduced into the cone, thus causing the tailings to pursue a spiral path from the center to the 20 upper periphery of the cone. Within the hollow shaft 17 is a rod 21 at the lower end of which is a float 22 which is freely movable in a vertical direction. The upper end of the rod is provided with an insulated contact 23 which engages a 25 companion contact 24 when the float is raised a sufficient distance. Closing this contact causes the speed of a pump 25 connected to the bottom of the cone to increase. This is effected through a variable speed regulator 26 of any convenient 30 type, operating in conjunction with a motor 27.

The pump 25, as previously stated, is connected to the bottom of the cone and discharges into a pipe 40 which communicates with the top of a secondary separating cone 51, preferably of 35 smaller size than the cone 16, but of similar construction. A pump 42 is connected to the bottom of the secondary separating cone and is arranged to operate at a variable speed by means (not shown) similar to the means shown in conjunction 40 with the primary separating cone. Material withdrawn from the bottom of the secondary cone is pumped by the pump 42 to one longitudinal compartment of a screen 43. Medium which is drained off the products on the screen 45 45 passes into a hopper 44 and thence into a sump 45 from which it is returned to classifier 28 by means of a pump 46.

As hereinbefore indicated, the medium-coated oversize is continuously introduced into the cone. At the same time conditioned medium from the 50 classifier 28 is introduced into the cone. This classifier is of novel construction and is more fully described in my copending application Serial No. 51,329, filed November 23, 1935. Briefly, this classifier comprises a cylindrical 55 upper section and a conical lower section. At the bottom of the conical section a conveyor housing 29 is connected. This housing contains a screw conveyor 30 which rises outside and obliquely 60 from the bottom of the conical section to approximately the top of the cylindrical section. The classifier is equipped with a centrally disposed vertical hollow shaft 31 provided with blades 32 in the cylindrical section and with an agitator 33 of egg-beater type construction in 65 the conical portion. Means (not shown) are provided for revolving the shaft so that the peripheral speed of the outside of the blades will not exceed about 150 feet per minute. Within 70 the hollow shaft is a rod 34 similar to that in the primary and secondary separating cones. This rod has a float 36 at its lower end which is freely movable in a vertical direction. When the float is raised a sufficient distance it closes contacts 36, 37 and permits a power source 38 to energize a

75 solenoid operated valve 39, which opens an outlet in the conveyor housing 29 positioned about mid-way up the housing.

A hydrometer 48, positioned within the classifier near the overflow level of the cylindrical section, is held horizontally by guides or pivoted (not shown) but is freely movable in a vertical direction. This hydrometer, when raised, serves to close contacts 48 and 49 and these contacts connected with an electrical circuit and a power source 10 (not shown) serve to open a solenoid operated valve 50 which introduces water into the sump 45, at the same time throttling down another solenoid operated valve 51 which introduces fresh medium into the same sump. The two valves 15 may, if desired, be operated by means of the same solenoid. A simple lever arm see-saw construction, well understood by those skilled in the art, will serve for this purpose.

Near the upper periphery of the classifier 28 is 20 a float 52 which when lowered will open another solenoid operated valve 53 and introduce additional medium into the sump 45.

A peripheral launder 90 having a partition 91 in it (provided with a vertically adjustable baffle 25 76) surrounds the upper edge of the medium classifier. This baffle may be adjusted to regulate the amount of medium flowing to the primary separating cone.

Tailings withdrawn from the upper periphery 30 of the primary separating cone 16, concentrates withdrawn from the bottom of the secondary separating cone 51, and middlings taken at the upper periphery of the secondary separating cone 35 are sent respectively to three parallel compartments in the long screen 43, which is of approximately 20 mesh.

The upper portion of the screen 43, that is the portion above the hopper 44, is a drainage section. Succeeding sections of the screen are 40 underlain respectively by hoppers 54, 55 and 56 and in these sections of the screen a counter-current washing operation of the tailings, middlings, and concentrates takes place. Fresh water is introduced on the outermost section of the screen through a spray bank 73, and the drainage therefrom passes into the hopper 56 and thence into a sand trap 57 which is similar in construction to the sand traps 6, 8, and 10, used in the preliminary washing operation. The overflow from this sand trap is forced by pump 58 into a second bank of sprays 59 in one of the mid-sections of the screen. The drainage from this mid-section passes into the hopper 55, and thence into a sand trap 60 from which the overflow is forced by pump 61 into a second bank of sprays 62. A third bank of sprays 63 is supplied with overflow water from a medium thickener 64. This overflow from the medium thickener is usually quite turbid. Drainage from the sprays 63 and 62 passes into the hopper 54 and thence 50 into a sand trap 65. The overflow from this sand trap is sent to the medium thickener 64. The sands withdrawn from the bottom of the three sand traps 65, 62, and 57, are sent to a classifier 66 in which the coarse sands and the medium are separated. The medium recovered in this classifier (which may be of any convenient design) is sent to the medium thickener 64. The sands from the classifier 66 are sent to 60 the ball mill circuit 12, 13 and join the sands from the sand traps 6, 8, and 10.

Washed concentrates are recovered from the end of the screen 43, washed tailings at this point are sent to waste, and washed middlings 75

are crushed to a size ranging from $\frac{1}{4}$ inch to $\frac{3}{8}$ inch in rolls 92 and sent back to the crushed ore bin 1 (for return to the circuit).

The underflow from the medium thickener 64 is moved by diaphragm pump 67 to a surge tank 68 which feeds through the solenoid valve 51 into the sump 45.

The overflow from the medium thickener passes into a froth trap 69. This froth trap is baffled so that froth, oil, etc., are caught and removed from the circuit. At a point slightly below the overflow of the froth trap is a "bleeder" 70 through which colloidal material and other contaminants in suspension may be bled off substantially continuously, and sent to the ore thickener 11. In this way such impurities may be removed from the medium circuit and prevented from fouling it. Underflow from the froth trap is forced by a pump 71 into the spray bank 63 and is there utilized for washing the concentrates, middlings and tailings.

In the froth trap is a float 72 which by well-known means, such as a solenoid-operated valve (not shown) may be caused to regulate the volume of fresh water introduced into the spray bank 73 on the screen 43, thereby permitting water balance in the circuit.

Coarse medium withdrawn by the spiral conveyor 30 from the medium classifier 28 may be sent to a medium grinding circuit comprising a ball mill 74 operated in closed circuit with the classifier 75. If, as is sometimes the case, the material withdrawn from the spiral conveyor 30 contains heavy sulphide or ore sands which might be worth recovering (or else undesirable medium constituents) the material withdrawn by the spiral conveyor 30 may be passed over a very fine screen (say 100 mesh) before it is sent to the ball mill circuit 75. Material from which the solid constituent of the medium is manufactured (such as galena) is contained in a bin 76 and from there fed into the medium ball mill circuit 75.

The classified product from the medium ball mill circuit is sent to the medium thickener 64.

Having in mind the flow-sheet of the process just described, the method of operation may be outlined as follows:

The feed from the crushed ore storage bin, 50 together with returned crushed middlings, is first countercurrently washed on the preliminary washing screen 2, mixed with medium in the box 14 and passed over the screen 15 from which excess medium, together with any contaminating 55 sands, is drained. The oversize of the screen 15 (now coated with medium) is introduced into the primary separator, together with conditioned medium from the classifier 28. In the primary separator the tailings, together with some of the 60 medium, are caused to pass outwardly in a spiral path to the upper edge of the separator and are then removed and taken to the screen 43. The rough concentrates from the primary separator are continuously withdrawn from the bottom 65 thereof, together with a portion of the medium, and pumped into the top of the secondary cone 41. The rate of withdrawal of the medium and concentrate from the primary secondary cone is governed by the density of the medium in the 70 bottom of the primary secondary cone or by the accumulation of concentrate at this point. If crowding occurs from either of these sources, the speed control mechanism 23, 24, 26, 27 increases the speed of the pump 25 and withdraws more 75 material, thereby overcoming the crowding.

In the secondary separating cone the process is repeated, except that a middling product is withdrawn from the upper periphery of the cone and sent to the screen 43. A cleaned concentrate is withdrawn from the bottom of the secondary separator and is also sent to one of the parallel partitions in the screen 43.

In the drainage zone on the screen 43 the greater portion of the medium is removed and (after automatic conditioning by addition of water from the valve 50 or of medium from the valves 51 and 53) the medium is pumped into the classifier 28. In this classifier three automatic controls are maintained. By means of the float 35, the segregated coarse material is withdrawn by the solenoid operated valve 39 and returned to the ball mill circuit 74, 75 where the medium is ground. Should the float 52 fall so that the level in the classifier 28 is too low to maintain a sufficient volume of flow to the medium wetting screen 15, the float 52 will cause more medium to be introduced into the circuit through the solenoid operated valve 53. Other means of control comprises the hydrometer 48 which serves to regulate the proportions of solids and liquids introduced into the sump 45 by opening or closing solenoid operated valves 50 and 51 respectively.

If further control is desired, the vertically adjustable peripheral lip 76 in the launder 90 surrounding the classifier 28 may be raised or lowered manually to control the volume of medium sent directly to the primary secondary cone 16.

The countercurrent washing system on the screen 43, which has already been described, permits maximum washing efficiency with a minimum quantity of water, thus reducing the volume of material which has to be handled in the medium thickener 64, at the same time permitting the balancing of the water used in the circuit.

Segregations of sandy material which might otherwise interfere in the separation are rapidly removed from the separating circuit at all points of segregation, so that interference from this source is completely eliminated.

The continual bleeding of colloidal material from the circuit through the drain 70 on the froth trap prevents an accumulation of such impurities in the circuit which would otherwise foul the medium.

When, as in the case of coal, the natural slimes 50 in the material can be utilized for making the medium, the preliminary washing step may be eliminated, but not otherwise.

In the case of coal, considerable fine coal may be caught in the sand traps 57, 62 and 65. In this case it is desirable to recover the fine coal at this point so that in place of the classifier 66 the apparatus shown in Fig. 2 may be substituted. This apparatus briefly comprises a cone 77 which in general is similar in construction to the medium 60 classifier 28. A peripheral launder 78 surrounds the upper edge of the cone and is provided with a drain 79 from which the overflow water may be sent to the medium thickener 64. A splash ring 80 is positioned concentrically in the upper portion of the cone 77. A hollow shafted agitator and float structure 100 of the separator in Fig. 2 is similar to that of the classifier 28 and is sufficiently shown in Fig. 2. However, when the float in this apparatus rises, it closes a circuit 81 equipped with contact points 82 and 83 and through a variable speed regulator 84 increases the speed of a pump 88 which withdraws material from the bottom of the cone. Means (not shown) are provided for revolving the hollow shafted 70 75 75

agitator so that the maximum peripheral speed of the agitating blades in the device will not exceed 150' per minute.

- If it should prove necessary to supply medium to the separating cone of Fig. 2 to increase the density therein, this is automatically accomplished through a valve 85 which is actuated by a hydrometer 86. The additional medium is added only to increase the density in the midsection of the cone. The overflow lip serves to discharge the very dilute medium just as clear water is decanted from a thickener. In other words, the separating vat performs the function of a thickener as well as a separating cone.
- About two-thirds of the way up on the cone an outlet 87 is provided. By means of a suction pump (not shown) fine coal which collects in the zone (near said outlet) together with medium may be continuously withdrawn from the cone, washed and recovered.

The coal withdrawn may be recovered by fine screening or by appropriate water classification in a highly diluted circuit.

- The outflow from the pump 88 is refuse or "bone" which may be treated in a manner similar to that for the fine coal withdrawn from the cone of Fig. 2. That is to say, it may be screened or classified so that the medium is recovered and the refuse is eliminated and sent to waste. Any very fine coal which leaves the separator of Fig. 2 through the pump 85 will automatically be eliminated from the circuit by bleeding through the medium trap 69 and the outlet 10.

- Fine coal may be recovered from the medium thickener as a froth which collects in the froth trap 69. If the amount of fine coal in the circuit is considerable, the amount removed as a froth may be increased by adding a small amount of oil into the wash water spray circuit which feeds into the medium thickener.

- While the apparatus which I have described is primarily adapted to separation wherein the density of the medium is intermediate the density of the two products to be separated, essentially the same process may be employed with a medium which is slightly lighter than the lightest constituent in the ore. However, in such case it is necessary to substitute jigs or like devices for the separating cones which I have illustrated and the auxiliary medium control and washing steps will be equally vital in controlling the separation.

In place of the pumps 25, 42, and 85, which I have shown for recovering material from the bot-

tom of the separating cones, air lifts may be substituted, in which case the volume of air rather than the pump speed would be regulated in order to produce an equivalent effect.

In place of the plurality of feed traps 51, 62, 565 which I have shown for removing the sandy material from the wash water a slightly inclined screen having a sand trap at its lower end may be substituted to provide the necessary counter-current wash for elimination of the sandy material, or a plurality of cones with a common spiral conveyor and valve control.

The overflow launders on the classifier 28 and on the sand traps 6, 8, 10, 57, 62 and 65 should be of sufficient capacity to serve as surge tanks, thereby preventing the associated pumps from sucking air when sand withdrawal valves, such as valve 39, are open.

Instead of the single screen 43 provided with the longitudinal baffles, a set of three individual screens could be employed. However, for simplicity of construction, I find that the apparatus illustrated is particularly effective.

In place of the secondary separating cone 41, it is possible to employ a jig of the conventional type which will permit the production of a concentrate and a middling. This jig, which replaces the secondary cone, may operate in the position shown for the secondary cone and using the medium; or the product may be separated in the presence of water alone after it has been screened and the medium removed by washing.

I claim:

A process for separating heterogeneous mixtures of ore fragments which comprises first washing the ore fragments with water, then washing the ore fragments with heavy medium comprising a suspension of finely divided solid particles in liquid, introducing the resulting medium-coated fragments together with the heavy medium into a separating chamber, withdrawing heavy fragments together with medium from the bottom of the separating chamber and introducing them into a second chamber, withdrawing heavy fragments together with medium from the bottom of the second separating chamber, withdrawing relatively lighter fragments from the top of the second separating chamber, removing medium from said relatively lighter fragments, crushing said relatively lighter fragments and returning them to the circuit with the fresh ore fragments.

CHARLES ERB WUENSCH.
